UNITED STATES PATENT OFFICE

PETER A. JOHNSON, OF BLACKFOOT, IDAHO.

STEAM-SEPARATOR.

No. 918,326.

Specification of Letters Patent.

Patented April 13, 1909.

Application filed March 21, 1907. Serial No. 363,532.

To all whom it may concern:

Be it known that I, PETER A. JOHNSON, of Blackfoot, in the county of Bingham and State of Idaho, have invented certain new and useful Improvements in Steam-Separators; and I do hereby declare the following to be a full, clear, and exact description of the invention, such as will enable others skilled in the art to which it appertains to 10 make and use the same.

My invention relates to an improvement in steam separators, the object being to provide a simple and efficient device for separating water or moisture from steam and thereby 15 insure the delivery of dry steam to the cylinders of steam engines.

With this object in view my invention consists in certain features of construction and combinations of parts as will be hereinafter 20 described and pointed out in the claims.

In the accompanying drawings, Figure 1 is a vertical section of my improvement and Fig. 2 is a plan view of the base or lower casting of the device.

25 A is a steam pipe to be connected to a suitable source of supply.

B is a pipe, the upper end of which extends above the lower end of pipe A, while its lower screw threaded end *a* is screwed into the floor 30 of the bottom casting C. Encircling pipe B is a pipe D, the upper end of which is screwed into a depending flange *b* of a cover plate E, the upper end of the latter being screwed upon the pipe A. The lower end of pipe D is 35 screwed into the upwardly projecting flange *c* of the bottom casting C. A water glass E' has its lower end connected with the interior of pipe B, its upper end being passed through the outer pipe D and connecting with the annular space between the two pipes B and D. 40 A drain pipe F communicates with the bottom of pipe B.

The bottom casting C is constructed similar to the steam inlet port of a steam engine cylinder. This bottom casting consists of 45 two rings *g*, *g'* cast in a single piece and united at opposite sides by the ribs or flanges *h*, thereby forming two curved steam passages *i*, *i'*, for the passage of dry 50 steam from the separator into the engine cylinder by means of an outlet pipe G to be connected with the throttle valve of the engine. A rod H is screwed into the floor of the bottom casting C, and is provided at suitable 55 intervals with horizontal plates *h'* which may or may not be perforated, which assist in

breaking up the steam and freeing it of its contained moisture.

The operation of the device is as follows: The steam passes downwardly through pipe 60 A and into the pipe B which is closed at its lower end by the floor of the bottom casting, which results in the steam flowing upwardly again through the annular passage *j* between the lower end of pipe A and upper end of 65 pipe B. The area of this annular passage is equal to the inner area of pipe A. The flow of steam from the annular passage *j* is downwardly through the annular chamber *k* between the pipes B and D, through the curved 70 passages *i*, *i'*, and into the outlet pipes G¹ and thence through the throttle valve of the engine cylinder. The effect of these reverse currents of steam in the pipe B, the downward current being met by the upward current, is to cause the separation of the water 75 or moisture contained in the steam and its deposition in the lower end of the pipe B from which it is withdrawn from time to time through the drain pipe F. The series of 80 horizontal plates *h'*, also assist in breaking up the currents of steam and the separation of the water therefrom. The inner pipe B is of considerable length which insures quite a distance through which the two oppositely 85 moving currents of steam must flow before the dry steam can escape and feed downwardly through the annular chamber or passage *k*. While these reverse currents of steam are flowing through this elongated 90 chamber they are subjected to complete periods of rest which intervene between the double strokes of the piston, which action facilitates the separation. When the engine 95 is stopped all condensation water is collected and engine may be started with the dry steam.

The device is of comparatively small cost as standard pipes are employed in its construction and the bottom casting is made in 100 a single piece.

Having fully described my invention what I claim as new and desire to secure by Letters-Patent, is:—

1. In a steam separator, the combination 105 of two concentric pipes forming an intermediate annular passage communicating with the upper end of the inner pipe, said inner pipe being open at its top and closed at its bottom, and the outer pipe closed at 110 its top and open at its bottom, a steam pipe entering and discharging into the upper end

of said inner pipe, and a bottom casting to which the two pipes are secured and having steam passages through it which register with the annular passage between the two pipes.

2. In a steam separator, the combination of concentric pipes forming an annular passage between them, said annular passage communicating at its upper end with the inner pipe, means at the lower end of said pipes forming an outlet for said annular chamber, a steam supply pipe discharging into the upper end of the inner pipe, said inner pipe closed at its bottom and the outer pipe closed

10 at its upper end, a standard in the inner pipe and obstructing devices on said standard.

15

3. In a steam separator, the combination with a bottom casting provided with two screw threaded flanges and intervening steam

20 passages, of two pipes screwed into said flanges and separated one from the other to form an intervening annular chamber, of a steam supply pipe extending downward into

the upper end of the inner pipe, and a cap covering the space between the steam supply 25 pipe and the outer pipe, substantially as set forth.

4. In a steam separator, the combination with two pipes one encircling the other and separated from one another to form an intervening annular steam passage, of a steam supply pipe extending downward into the upper and open end of the inner pipe, a cap for closing the upper end of the outer pipe, a bottom casting to which the lower ends of both 30 35 pipes are secured, and provided with openings for the passage of dry steam through the casting and into the outlet pipe, substantially as set forth.

In testimony whereof, I have signed this 40 specification in the presence of two subscribing witnesses.

PETER A. JOHNSON.
